(57) **CLAIM**

The ornamental design for a support member for roof panel offset, as shown and described.

DESCRIPTION

FIG. 1 is a perspective view of a support member for roof panel offset, in accordance with a first embodiment;

FIG. 2 is a top view thereof;

FIG. 3 is a bottom view thereof;

FIG. 4 is a first side view thereof;

FIG. 5 is a second side view thereof;

FIG. 6 is a front view thereof;

FIG. 7 is a rear view thereof;

FIG. 8 is a perspective view thereof, installed in a roof system;

FIG. 9 is a perspective view of a support member for roof panel offset, in accordance with a second embodiment;

FIG. 10 is a top view thereof;

FIG. 11 is a bottom view thereof;

FIG. 12 is a first side view thereof;

FIG. 13 is a second side view thereof;

FIG. 14 is a front view thereof;

FIG. 15 is a rear view thereof; and,

FIG. 16 is a perspective view thereof, installed in a roof system.

The evenly broken lines represent parts of the article as well as environmental subject matter of an exemplary roof system. The dot-dashed broken lines represent the boundaries of the claim. None of the broken lines form part of the claimed design.

1 Claim, 10 Drawing Sheets
